UNITED STATES PATENT OFFICE.

ELIE W. LABOMBARDE, OF NASHUA, NEW HAMPSHIRE.

COMBINATION FEED FOR SHEET MATERIAL.

1,112,811.

Specification of Letters Patent.

Patented Oct. 6, 1914.

Application filed June 8, 1912. Serial No. 702,418.

To all whom it may concern:

Be it known that I, ELIE W. LABOMBARDE, a citizen of the United States, and a resident of Nashua, in the county of Hillsboro and State of New Hampshire, have invented certain new and useful Improvements in Combination Feed for Sheet Material, of which the following is a specification.

This invention relates to mechanism for feeding blanks of sheet material from a pile or stack, one at a time, and the invention refers especially to such feeding mechanism adapted to supply the blanks singly to folding machinery in making boxes or cartons.

One of the objects of the invention is to provide mechanism adapted to feed from the top or the bottom of a pile or stack, according to the work to be performed.

Another object is to provide means for increasing the speed of movement of each blank leaving the pile.

A further object is to provide an improved friction reducing table for the top feed mechanism.

A further object is to provide means for adjusting the combing wheel or wheels of the top feed devices to compensate for wear of the friction surfaces of such combing wheels.

To the above ends the invention consists in the improvements which I shall now proceed to describe and claim.

Of the accompanying drawings:—Figure 1 is a side elevation of my improved mechanism, said figure also indicating by dotted lines the position of some of the parts when the mechanism is used for feeding from the bottom of a stack or pile. Fig. 2 is a view similar to Fig. 1 but indicating some of the parts in section. Fig. 3 is a plan view. Fig. 4 is a detail elevation showing the gearing for driving the combing roll shaft. Fig. 5 is a view similar to a portion of Fig. 2 but on a larger scale to show the specific structure of the inclined table and its friction reducing facing sheets. Fig. 6 is a detail side elevation and also a cross section of one of the retarders on a larger scale than in Fig. 5. Fig. 7 is a detail elevation illustrating the gearing for driving the speed rolls. Figs. 8 and 9 are respectively a detail side elevation and detail front elevation of the structure which provides for adjusting the combing wheel shaft to compensate for wear of the peripheries of the combing wheels.

The same reference characters indicate the same parts in all the figures.

Mounted in the frame 12 of the machine are shafts 13, 14, the latter of which will be hereinafter referred to as the "drive" shaft. Said shafts carry pulleys 15, 16, for the belts 17, 18, which are employed for taking the blanks after they have been detached from the pile or stack, so as to convey or carry said blanks singly to the folding or other machine which is to be supplied with said blanks.

As best shown in Fig. 3, two slotted bars 19 support side guides 20, said side guides being adjustable along the bars 19 and held in adjusted positions by suitable screw devices 21. Between the side guides 20 are the under feed belts 22 supported at one end upon a drum 23 carried by a shaft 24 and supported at the other end upon a shaft or roll 25, this structure being similar to that illustrated and described in United States Letters Patent 1,011,829, granted to me December 12, 1911. A pulley 26 on the shaft 24 is connected by a belt 27 with a pulley 28 on shaft 14. As shown in Fig. 2 the pulley 28 is of considerably less diameter than the pulley 16. The shafts 13 and 14 are geared to rotate as indicated in Fig. 7, but since the pulleys 28 and 26 are of substantially the same diameter, and since the drum 23 which transmits motion to the feed belts 22 is of substantially the same diameter as the pulleys 28 and 26, the belts 22 travel at considerably less speed than the belts 17 and 18. The purpose of this will be explained hereinafter.

A shaft 30 supports flanged idle pulleys 29 which guide the belts 22, said shaft 30 also having a roll 31 which operates with the tip of the adjustable stop finger 32 in the same manner as explained in the patent referred to. A pair of stack shapers or stops 33 perform the same function as explained in said patent.

Two brackets 34 are mounted at their lower ends upon a pivot rod 35, and said brackets are provided with notched catches 36 the notches of which engage pins 37 projecting from the frame to hold said brackets in position as shown by full lines in Figs. 1, 2 and 4.

The outer ends of the brackets are connected by a cross bar or handle 38. Rubber faced combing-wheels 39 are carried by a

160

165

110

shaft 40 mounted in the brackets 34, said shaft having a gear 41 which is driven by means of a gear 42 on shaft 24 through intermediate pinions 43. As best shown in Fig. 4, the intermediate pinions 43 are carried by a swinging arm, the axis of which coincides with the axis of the shaft 40, the construction being such as to preserve operative engagement of the gearing when the combing-wheel shaft is vertically adjusted, as herein-after described.

Ratchet segments 44 are pivoted at 45 to the brackets 34, said segments having sockets 46 for the purpose presently described. 15 Pawls 47 carried by a shaft 48, engage the ratchet segments, said shaft having a handle 49 and an arm 50 to which one end of the spring 51 is connected so as to normally hold the shaft 48 and the pawls 47 in the position 20 shown in Fig. 4.

The inclined table comprises a metal frame 52 with a middle supporting surface 53 usually of wood for the sake of lightness and has end rods 54 removably fitting the 25 sockets 46. Said table can be easily removed by slipping said rods out of said sockets, and its angle of inclination can be adjusted by grasping the handle 49, moving the pawls 47 away from the ratchet segments in case it be desired to lower the table, and then releasing the handle 49 to permit the spring 51 to return the pawls into holding engagement with the segments. Of course, if the table is to be swung upwardly to a steeper angle 35 of inclination, it is only necessary to lift the outer edge of the table, the teeth of the segment 44 riding over the pawls 47.

A pair of plates or brackets 55, adjustably secured to the table frame by clamps 56, 40 support side guides 57 so that said guides can be set in alinement with the guides 20.

A rod 58 is supported at its ends in brackets 34 and in turn supports collars or brackets 59 (see Figs. 2 and 5) said brackets carrying shoes 60 for the rubber retards 61. 45 (See also Fig. 6). The collars or brackets 59 can be adjusted along the rod 58 and secured with the shoes 60 at any desired angle of inclination, by means of screws 62.

The inclined table is provided with friction-reducing surface material preferably of smooth metal such as tin. The large section 63 of the tin facing covers practically the entire area of the board 58. A strip 64 of the tin or similar material is adjustably held between members of the table, as shown in Fig. 5. The lower edge of this tin strip 64 extends well under the combing-wheels, and covers all except the forward portions or tips of the rubber retarding strips 61. By means of adjusting screws 65 mounted in the brackets or collars 59 and extending up through apertures in the forward portions of the shoes 60, the tips of the friction retarders 61 can be adjusted to compensate for

wear or to vary the distance between their upper faces and the peripheries of the combing-rolls. If the covering or protecting strip 64 were not present, then when the pile of blanks is low, or, in other words, when there are a few blanks left on the table, their lower edges would contact with the retards and be prevented from being fed forward by the combing-wheels. The said strip 64 being adjustable or interchangeable with other strips of different sizes, will provide for running through blanks of varying qualities of material, even down to the last one. The strip 64 will be set farther back for heavy material than for light material, heavy material requiring a greater frictional retard, and also a heavier or stronger combing-action.

It is frequently desirable to change the elevation of the combing-wheels, especially to 35 compensate for wear of their rubber covered peripheries. To effect this adjustment, 1 provide the pivot rod 35 for the brackets 34, with eccentrics 66, said eccentrics being secured to the rod by screws 67. The brackets 90 or arms 34 have hubs 68 mounted on said eccentrics 66. (See Figs. 8 and 9).

One end of the rod 35 is squared or otherwise formed to be engaged by a wrench, a portion of the rod being screw-threaded to 95 enable a set nut 70 to be employed, said set nut co-operating with the frame 12 in which the rod 35 is mounted, to clamp the rod 35 and prevent it from rotating. By loosening the nut and rotating the rod 35 and its eccentric 66 more or less, and then tightening up the nut 70, the brackets 34 may be adjusted so that the shaft 40 and its combing-wheels 39 may be adjusted for the purpose herein-before described. Of course, the pivoted catches 36 will readily permit of this adjustment without releasing the brackets so that the frame might swing.

When the parts are in the position indicated in Figs. 2 and 3 and by full lines in Fig. 1, the pile or stack of blanks will be placed upon the table, and the angle of inclination of the latter fixed so that the blanks will be caused to slide toward the combing-wheels. The operator will, of course, so shape the pile or stack that the top blank will slide to position just beyond the extreme edge of the strip 64 to bear against the uncovered portions of the retarders but so as to be combed off by the 110 wheels 39, the blanks below the top one having their front edges at further points rearwardly. The drive of the combing-rolls is positive through the gearing herein-after described, but said combing wheels, 115 and also the table, may be quickly taken away from the position shown in Fig. 2 when it is desired to feed from the bottom of a pile or stack placed on the belts 22 between the guides 20. To effect this 120

70

change, the table is bodily removed by drawing the ends rods 54 out from the sockets 46 of the ratchet segments. - Then the catches 36 are released from the fixed pins 5 37 and the operator by grasping the handle bar 38 will swing the brackets and all of the mechanism carried thereby outwardly and downwardly, and allow said parts to remain suspended in the position indicated 10 by dotted lines in Fig. 1. While it is not always necessary to remove or swing these parts as described, especially if comparatively small blanks are to be fed, yet it is desirable to do so in order that the operator 15 may more readily place and manipulate a pile or stack of blanks on the belts 22. The top feed mechanism including the combing-wheels, is best for light material, and for wide work, while the bottom feed, (meaning 20 the employment of the belts 22 to directly support the pile or stack) is preferable when the blanks are of heavy material. Sometimes the differences of shape and scoring of the blanks renders it desirable to employ the top feed in preference to the bottom feed, or vice versa.

The adjustable middle stop finger 32 is useful even when the top feed is employed so that there will never be but one blank at 30 a time on the belts 22, because said finger provides an extra stop gage.

Referring especially to Fig. 7, it will be seen that the shaft 13 of pulley 13 is provided with a gear 71 meshing with a gear 35 72 on the shaft 14 of pulley 16, thereby insuring travel of the contacting stretches of 75 the belts 17, 18 in the same direction and at uniform speed. The blanks are delivered to the nip of the belts 17, 18, from the belts 40 22 between two rolls 73, 74, which, for convenience, I refer to as "speed" rolls. These two rolls have intermeshing pinions, and the pinion of the lower roll 74 is engaged by an intermediate pinion 75, which, in turn, 45 meshes with and is driven by the gear 72. By referring to Fig. 2 in connection with Fig. 7, it will be seen that the peripheral speed of the rolls 73, 74, will be substantially 50 the same as the speed of the belts 17, 18, and therefore, for the reasons and owing to the construction hereinbefore described, said rolls 73, 74, have a peripheral speed greater 55 than the speed of travel of the belts 22. When the blanks to be fed are rectangular or have straight and parallel front and rear edges, this increase of travel as they leave the belts 22 will not be so necessary, and by ordinary change speed gearing, the speed 60 of travel might be made uniform. The 65 device illustrated and described, however, is prepared for the following reasons:—

When the blanks have projecting tongues, 70 they are liable to be fed in such manner (or, in other words, too close together) that such

tongues may overlap and become interengaged or caught so that several blanks might be folded up as a tube instead of as separate boxes, by the folding mechanism which is to be supplied. This action is for 75 the reason that as soon as one blank passes the stop finger 32, or has been advanced from the top of a pile by the combing-wheels, the next blank is instantly engaged. When the blanks reach the speed rolls 73, 75 80 74, however, they are, each of them, instantly pulled away from the following one or ones so as to increase the space between the rear edge of each blank and the front edge of the next one, thereby avoiding liability of any tongues or projecting portions being interengaged or caught when the blanks are folded up.

It will now be understood that I have provided mechanism which will either remove 85 blanks singly from the top of a pile (combing-wheels 39), a carrier (belts 22) for advancing the blanks so removed and means (the finger 22, or the stack shapers 33, or both) cooperating with the carrier in 90 such manner that a pile of blanks can be placed on the carrier and will be retained thereon while the carrier advances the bottom blank of said pile.

I claim:—

1. A mechanism of the character described, comprising a feeder for removing blanks singly from the top of a pile, a carrier for advancing the blanks so removed, and means cooperating with said carrier to 100 permit a pile of blanks to be placed on the carrier and to be retained thereon while the carrier advances the bottom blank of the pile.

2. A mechanism of the character described having sheet feeding belts and a stop to prevent the passage of more than one blank at a time, and a combing wheel and table adjacent said belts to supply blanks singly to said belts from the top of a pile 105 on the table, said wheel and table being movable to permit a pile of blanks to be placed on the belts.

3. A mechanism of the character described, comprising a feeder for removing blanks singly from the top of a pile, a carrier for advancing the blanks so removed, means cooperating with said carrier to permit a pile of blanks to be placed on the carrier and to be retained thereon while the carrier advances the bottom blank of the pile, and means for increasing the space between the blanks as they leave the carrier.

4. A mechanism of the character described, comprising a feeder for removing 125 blanks singly from the top of a pile, a carrier for advancing the blanks so removed, means cooperating with said carrier to permit a pile of blanks to be placed on the carrier and to be retained thereon while the car-

rier advances the bottom blank of the pile, and two sets of guides in alinement with each other for directing the side edges of the blanks.

5. A mechanism of the character de-

scribed, comprising a feeder for removing blanks singly from the top of a pile, a car-

rier for advancing the blanks so removed, means coöperating with said carrier to per-

10 mit a pile of blanks to be placed on the car-

rier and to be retained thereon while the car-

rier advances the bottom blank of the pile,

and an adjustable inclined table for supply-

ing blanks to said feeder.

15. A mechanism of the character de-

scribed, comprising a feeder for removing blanks singly from the top of a pile, a car-

rier for advancing the blanks so removed, means coöperating with said carrier to per-

20 mit a pile of blanks to be placed on the car-

rier and to be retained thereon while the car-

rier advances the bottom blank of the pile,

and an adjustable inclined table for supply-

25 ing blanks to said feeder, said table having

a surface of smooth sheet metal.

7. A mechanism of the character de-

scribed, comprising a feeder for removing blanks singly from the top of a pile, a car-

rier for advancing the blanks so removed, means coöperating with said carrier to per-

30 mit a pile of blanks to be placed on the car-

rier and to be retained thereon while the car-

rier advances the bottom blank of the pile,

and an adjustable inclined table for supply-

35 ing blanks to said feeder, said table having

an adjustable facing strip near the said

feeder.

8. A mechanism of the character de-

scribed, comprising an upwardly facing con-

40 tinuously movable feeder, and a downwardly facing continuously movable feeder, whereby sheets may be fed from the bottom of a

pile or from the top of a pile, the relationship of each feeder to its pile being constant

45 in operation, and one feeding through the

other.

9. A mechanism of the character de-

scribed, comprising an upwardly facing con-

tinuously movable feeder, and a downwardly

50 facing continuously movable feeder, one

feeding through the other, whereby sheets may be fed from the bottom of a pile, or from the top of a pile, one of said feeders being displaceable relatively to the other.

10. A mechanism of the character de- 55

scribed, comprising a carrier for blanks, a

table for supporting a pile of blanks, combing-rolls for removing blanks singly from

the top of the pile, pivoted brackets sup-

porting said combing-rolls said brackets and 60

combing-rolls being displaceable to inopera-

tive position and means for locking said

brackets with the combing rolls in fixed op-

erative position.

11. A mechanism of the character de- 65

scribed comprising a carrier for blanks, a

table for supporting a pile of blanks, combing-rolls for moving the blanks singly from

the top of the pile, pivoted brackets sup-

porting said combing - rolls, said brackets 70

having a connecting handle-bar, the brackets and the combing-rolls being displaceable to

inoperative position, and means for locking

said brackets with the combing-rolls in fixed

operative position.

12. A mechanism of the character de-

scribed, comprising a continuously movable

feeder for operating on the bottom sheet of

80 a pile, a continuously movable feeder for op-

erating on the top sheet of a pile and ad-

apted to feed through the mechanism of

the first-mentioned feeder, the relationship

of each feeder to its pile being constant in

operation, and arresting means for prevent-

ing the feeding of more than one sheet at a

85 time.

13. A mechanism of the character de-

scribed, comprising a carrier, an inclined

table, adjustably mounted eccentrics, brack-

ets mounted on said eccentrics, and combing- 90

wheels supported by said brackets whereby

adjustment of the eccentrics will vary the

relationship of the combing-wheels to the

carrier.

In testimony whereof I have affixed my

signature, in presence of two witnesses.
